UNITED STATES PATENT OFFICE.

FALKLAND R. A. MACKINNON, OF GRAND RAPIDS, WISCONSIN, ASSIGNOR
OF ONE-HALF TO JOHN SCHNABEL, OF GRAND RAPIDS, WISCONSIN.

WAGON STAKE OR STANDARD.

SPECIFICATION forming part of Letters Patent No. 755,024, dated March 22, 1904.

Application filed May 18, 1903. Serial No. 157,651. (No model.)

To all whom it may concern:

Be it known that I, FALKLAND R. A. MACKINNON, a subject of the King of Great Britain, residing at Grand Rapids, in the county of 5 Wood and State of Wisconsin, have invented a new and useful Wagon Stake or Standard, of which the following is a specification.

The ordinary wagon-stake now generally employed is usually fitted in a socket mortised 10 in the bolster. These sockets being comparatively large weaken the bolsters, so that they often break, especially when heavy strains are brought to bear on the stakes.

It is the object of this invention to provide 15 a structure which will not weaken the bolster to a material degree, said structure being practically indestructible, strong, rigid, and at the same time capable of being readily and cheaply manufactured.

20 The preferred form of construction is illustrated in the accompanying drawings, where-
in—

Figure 1 is a side elevation of a portion of 25 a bolster, showing the improved stake applied thereto. Fig. 2 is a longitudinal sectional view through the same. Fig. 3 is a top plan view, and Fig. 4 is a perspective view of the stake detached.

Similar reference-numerals indicate 30 corresponding parts in all the figures of the drawings.

In the embodiment herewith illustrated the portion of the bolster shown is designated by the reference-numeral 10 and may be of any 35 well-known form having the usual wear-plate 11. Upon the end of this bolster is mounted the improved stake, (designated as a whole by the reference-numeral 12.) The stake is constructed of sheet metal and comprises a tubular shell 13, having on its outer side a longitudinally-disposed flange or rib 14, constituting a brace. This rib tapers toward its upper end, and its lower end is adapted to rest upon the bolster. It is formed by bending the side 40 margins of the sheet metal outwardly and securing them together by rivets or other suitable fasteners 15. The tubular shell is preferably, though not necessarily, provided with

openings 16 to receive chains or other load-
binders.

In order to secure the stake to the bolster, a depending shank 17 is employed which extends within the shell and is riveted thereto, as shown at 18. This shank passes vertically through the bolster, and a nut 19 is threaded 50 upon its lower end, said nut bearing against a washer 20. The flange or brace is also secured to the bolster, and for this purpose links 21 are riveted at their upper ends, as shown at 22, to intermediate portions of said flange. 55 The lower ends of the links embrace the bolster and are fastened thereto by a horizontally-disposed bolt passing through the bolster. With this construction it will be seen that a very small opening only need be made through 60 the bolster, so that the same is not materially weakened. The stake itself is very durable, being formed of metal, and it will be seen that it can be manufactured at small cost, as the necessary bend to the sheets and riveting 65 of the elements can be readily accomplished. The flange bearing upon the bolster and located on the outer side of the shell greatly strengthens the stake, so that it will resist 70 great outward pressure.

75 From the foregoing it is thought that the construction, operation, and many advantages of the herein-described invention will be apparent to those skilled in the art without further description, and it will be understood that 80 various changes in the size, shape, proportion, and minor details of construction may be resorted to without departing from the spirit or sacrificing any of the advantages of the invention.

Having thus described my invention, what I 85 claim as new, and desire to secure by Letters Patent, is—

1. A wagon-stake comprising a tubular shell 90 formed of sheet metal and adapted to rest at its lower end upon the bolster or other support of a vehicle, said sheet metal having its upright margins outturned and extending to the bottom of the shell and secured together and tapered to form a longitudinal brace.

95 2. A wagon-stake comprising a continuous

tubular shell arranged to rest upon the bolster and formed of sheet metal having its side margins outturned and fastened together forming a longitudinal brace on the exterior of the tubular shell.

3. A wagon-stake comprising a tubular shell formed of sheet metal having its side margins turned outwardly and tapered, said margins resting against each other and secured together, a depending shank secured within the

shell, and links attached to intermediate portions of the brace.

In testimony that I claim the foregoing as my own I have hereto affixed my signature in the presence of two witnesses.

FALKLAND R. A. MACKINNON.
